UNITED STATES PATENT OFFICE.

WALTER S. YOUNG, OF BROADHEAD, WISCONSIN, ASSIGNOR OF ONE-HALF
TO DOUGLAS TAYLOR, OF SAME PLACE.

HAMMOCK-SUPPORT OR TENT-FRAME.

SPECIFICATION forming part of Letters Patent No. 519,898, dated May 15, 1894.

Application filed August 28, 1893. Serial No. 484,235. (No model.)

To all whom it may concern:

Be it known that I, WALTER S. YOUNG, a citizen of the United States, residing at Broadhead, in the county of Green and State of Wisconsin, have invented certain new and useful Improvements in Hammock-Supports or Tent-Frames, of which the following is a specification.

The object of this invention is to construct a hammock support and tent frame in which a tripod frame is employed to support each end of a back bone, and intermediate cross-bars having a connection with the back bone which support the canopy or tent top, and an adjustable riser connected to the back bone.

In the accompanying drawings, Figure 1, is a plan view showing my improvements. Fig. 2, is a side elevation. Fig. 3, is a vertical section on dotted line *a*, Fig. 1. Fig. 4, is a vertical section on dotted line *b*, Fig. 1. Fig. 5, is an end elevation of the tripod frame as seen from the inside.

The tripods consist of bars 1 and 2, connected in a pivotal manner by the bolts 3, their upper ends are connected by a cross-bar 4, the bar 1, connected thereto by a bolt 5, and the bar 2, having its upper end slotted and a bolt 6, entering the slot, clamps the parts together. The remaining bar 7, of the tripod 30 has a pivotal connection with the back bone 8, of the support, and passes between the bars 1 and 2 above their connection with each other, and a hook or link 9, connects the bar 7, with the bolt 3. The ends of the back bone 35 are cut on a bevel and have notches 10, within which are seated the cross-bars 4, and a pin or stud 11, secured to the back bone enters a hole 12, in the center of the cross bar 4, forming a connection between it and the back 40 bone and hooks 13, connected to the cross-bar engage staples driven into the back bone which completes the connection of the tripod with the back bone. To the under side of the back bone are pivotally connected intermediate cross-bars 15, having their ends provided with a horizontal groove 16, and the ends of the cross-bar 4, formed with a like groove. In this instance a rope 17, is placed in the grooved ends of the cross-bars and turn but- 45 tons connected with the ends of the cross bars hold the rope within the grooves. To

the bolts 3, is connected a hook 14, and to the hook is connected a wire 18, having its free end in spiral form and capable of being turned into the ground serving as an anchor for the support against being blown over by high winds. A riser 19, is connected to the back bone by links 20, in such a manner that it may be folded against the upper surface of the back bone, and a hook 21, connects one end thereof with the back bone when it is in its elevated position. In this instance it is intended to locate the rope in a hem in the canopy or tent top in such a manner that the rope will enter the grooves in the 65 ends of the cross-bars, the riser is then elevated and secured in such position, the bars forming the tripod holding each end of the back bone in proper position. The tent top has the sides of the tent connected thereto, 70 and the whole supported in the same manner as the canopy top. By means of the slotted end of the end cross-bars the parts may be separated in order that the bar may be placed between the side bars of the tripod, 75 or for ease in folding or shipping. To the bars 7, between their connection with the back bone and link connection with the side bars of the tripod are secured supports 22, for the hammock, consisting of a strong rope 80 looped around a pin and around the bar.

I claim as my invention—

1. In a hammock or tent frame, a back bone, a cross bar connected to each end thereof, and a tripod supporting each end of the back bone 85 consisting of two bars having a pivotal connection, and a connection with the cross bar, a third bar having a connection with the back bone, and a link connection with the other bars of the tripod.

2. In a hammock or tent frame, a back bone, a cross bar connected to each end thereof, and a tripod supporting each end of the back bone, consisting of two bars having a pivotal connection, and a connection with the cross bar, 95 a third bar having a connection with the back bone, a link connection with the other bars of the tripod and an anchor for the tripods consisting of a spiral pin capable of being turned into the ground, and a connection between the pin and tripod.

3. In a hammock support or tent frame, a

back bone a cross-bar connected to each end thereof, and a tripod for each end of the back bone, two bars of which connect with the cross-bar the third bar having a connection 5 with the back bone and intermediate cross-bars having a connection with the back bone.

4. In a hammock support or tent frame, a back bone, a cross-bar connected to each end thereof, and a tripod for each end of the back 10 bone, two bars of which connect with the cross-bar, the third bar having a connection with the back bone and intermediate cross-bars having a connection with the back bone, the ends of the cross-bars and intermediate 15 cross-bars provided with means for holding the top in position.

5. In a hammock support or tent frame, a back bone, a cross-bar connected to each end thereof, and a tripod for each end of the back

bone, two bars of which connect with the 20 cross-bar, the third bar having a connection with the back bone, and intermediate cross-bars having a connection with the back bone, the end cross-bars and intermediate cross-bars provided with horizontal grooves, and 25 buttons closing the ends of the grooves.

6. In a hammock support, and tent frame, a back bone, suitable supports therefor, and a riser located above the back bone, and extending lengthwise thereof, links connecting 30 the riser to the back bone, and a hook connection with the back bone holding it in its elevated position.

WALTER S. YOUNG.
